UNITED STATES PATENT OFFICE.

CARROLL C. FIGGE, OF CHICAGO, ILLINOIS.

ROOF AND SHINGLE SECURING MEANS.

Application filed April 23, 1923. Serial No. 633,823.

This invention relates to an improvement in roofs and in the means for securing shingles to a roof. Among the objects of the invention are: to provide a roof in which the exposed ends of the shingles are held down without perforating them at such ends; to provide a clamp which will engage a plurality of shingles and hold them in place with the least possible securing means; to provide a clamp which engages the exposed end of a shingle to prevent it from being raised and from curving or warping; to provide a clamp which not only holds the shingles in place but provides means for guiding the next layer of shingles; to provide a shingle holding clamp which is not objectionably visible when the roof is completed; and in general to provide the construction herein shown and described.

20 In the drawings, Fig. 1 is a plan view of a portion of a roof constructed in accordance with the principles of this invention; Fig. 2 is a section taken on the line 2—2 of Fig. 1; Fig. 3 is a section taken on the line 3—3 of Fig. 1; Fig. 4 is a section taken on the line 4—4 of Fig. 1; and Fig. 5 is a perspective of one of the fastening clips.

The fastening means or clip 1 for securing and holding the shingles in place is preferably made up of a single piece of sheet material usually tinned or galvanized, and in this example, the sides 2 and 3 are offset or raised from the body portion by means of shoulders 4, the sides being disposed at a right angle to each other. At the opposite ends of the sides are ears 5 bent over upwardly parallel to but spaced from the sides substantially the thickness of a shingle which they are to engage. This clip is provided with a hole 6 in the body portion through which a shingle nail 7 is inserted. It may also be formed with nail holes 8 in the sides 2 and 3 and with other nail holes 9 and 10 in the body portion so that if a shingle nail inserted in any one of the holes should happen to extend into a space between the roof boards, it would still be possible to fasten the clip in place to the roof boards through one or more of the other holes.

In using this clip on a roof as shown in Fig. 1, a lower course of shingles is held in place by clips applied at the upper edges thereof and the next course is guided and the lower ends are held in place by the projecting ears 5 of the fastening clips. In

the example shown, the shingles are substantially square with the opposite corners disposed in line horizontally and vertically.

These shingles are laid in courses, the shingles 11 in one course being preferably overlapped by the shingles 12 in the next course, and these in turn being overlapped by the shingles 13 of the next course, and so on, the lower points of one course being disposed between those of the adjacent courses, both above and below it, in a well known manner.

In applying the clips, the shingles of the lower course 11 are laid in place and the clip 1 is applied with the corner of the meeting edges 2 and 3 uppermost, the clip being disposed adjacent but not at the upper corner of the shingle. The shoulders 4 of the sides thereupon form guides for placing the shingles 12 staggered with respect to the course below and adjacent the clip, and when this course of shingles 12 is nailed in place by clips at their upper corners, shingles 13 of the subsequent course are located in position by inserting the lower corner thereof under the ears 5 of the clip which holds the second course of shingles 11 in place. Thus each clip not only holds in place the shingles through which a nail 7 is inserted, but also by the engagement of the sides 2 and 3, it holds the adjacent shingles 12 in the next course in place and by the engagement of the ears 5 it holds the lower end of the shingle 13 of the subsequent course in place. All this is accomplished by means of a single shingle nail which is inserted through any one of the holes in the clip. Of course if desired, nails may be inserted through the holes 8 as well as through one or more of the holes 6, 9 and 10 in the body portion of the clip but this is not ordinarily necessary and a single nail will suffice for each clip.

It will be observed that each clip is entirely covered by the corner of the shingle which engages under the ears 5, with the exception of the ears themselves. As this clip is usually made of bendable sheet material the ears 5 may be tapped lightly after a shingle is inserted thereunder which will bind the extremity of the shingle in place. When the roof is complete the clips are all covered with the exception of the ears 5, and these are so small that they are scarcely noticeable and are not at all objectionable. The clips not only hold the shingles in place

but also they act as guides for spacers for laying the shingles so that after the first two courses are in place all the subsequent ones will be properly positioned automatically.

5. I claim:

1. A shingle holding means for angular butt shingles having a portion for attachment to a shingle of one course and having projecting ears for compressive engagement

10 with the lower angular end of a shingle in an overlying course, and having lateral projections at an angle to each other for engaging the sides of shingles in an intermediate course.

15 2. A shingle holding clip having a portion for engagement with a shingle of one course with ears for compressive engagement with the edge of a shingle of an overlying course, and with an offset side projection at 20 an angle to the access of the shingle for engaging the edge of a shingle of an intermediate course.

25 3. In a roof, the combination with angular butt shingles laid in a diamond-pattern with adjacent staggered courses, and a single piece clip having offset portions for engaging shingles by compression in three adjacent courses, the said portions including ears 30 bendable to engage the outer surface over the edges of the angular end of the outermost shingle.

35 4. In a roof, the combination with rectangular shingles in diamond patterned courses, and those in one course staggered with respect to the adjacent courses of a single piece clip having angular shoulders forming an angular recess and with overlapping ears 40 for engaging and positioning four shingles of three adjacent courses, and fastening

means inserted through the clip and through 40 one course only for holding all of the four shingles engaged thereby in place by compression.

5. In a roof, rectangular shingles angularly disposed in overlapping courses, a securing device for each shingle having angular raised edges for engagement with the edges of two shingles in the next course and ears at the end of the edges for overlapping 45 the angular extremity of a shingle of the second course, and a single fastening for the securing device which is covered by the overlapping of the shingles in the said second course.

6. A roof composed of angular butt shingles in overlapping courses, the butts of the shingle of one course being staggered with respect to those of an adjacent course, a single piece clip attachable to the upper end 50 of one shingle having means for positioning, engaging, and holding down the edges of the shingles of the next course and having overlapping ears bendable over the adjacent edges to engage by compressing the surface of the angular extremity of the shingle in the next overlying course and thereby to position it with respect to the courses below.

7. A shingle holding clip comprising a flat body portion with sides raised at an angle to each other and with overturned ears at 55 the ends of the sides, the sides adapted to engage over the edges of adjacent rectangular shingles arranged angularly end to end and the ears to engage over the adjacent edges of the butt of a staggered shingle in the overlying course.

CARROLL C. FIGGE.
